Primary Examiner — Selina Sikder*(74) Attorney, Agent, or Firm* — Dorsey & Whitney LLP(57) **CLAIM**

The ornamental design for a housing for electronic circuitry, as shown and described.

DESCRIPTION

FIG. 1 is an isometric view of a housing for electronic circuitry, presenting the top, front and left side.

FIG. 2 is an alternate isometric view of the housing for electronic circuitry as shown in FIG. 1, presenting the top, back and right side.

FIG. 3 is a top view of the housing for electronic circuitry as shown in FIG. 1.

FIG. 4 is a bottom view of the housing for electronic circuitry as shown in FIG. 1.

FIG. 5 is a back view of the housing for electronic circuitry as shown in FIG. 1.

FIG. 6 is a left side view of the housing for electronic circuitry as shown in FIG. 1; and,

FIG. 7 is a detail view of the housing for electronic circuitry, presenting portions of the back and right side as shown in FIG. 2.

The broken lines in the drawings show environmental structure and form no part of the claimed design.
